SPRAY HEADER FOR FOOD PROCESSING CONVEYOR SYSTEMS OR THE LIKE

Charles W. Titus, Wake County, N.C., assignor to Watson
Seafood and Poultry Co., Inc., Raleigh, N.C.

Filed June 3, 1966, Ser. No. 2,536

Term of patent 14 years

(Cl. D91—1)

FIG. 1

FIG. 2

FIG. 1 is a perspective view of a spray header for food processing conveyor systems or the like, showing my new design; and

FIG. 2 is a side elevational view of the same.

The beam and connected hose shown in broken lines in, respectively, FIGS. 1 and 2, are included for illustrative purposes only.

What is claimed is:

The ornamental design for a spray header for food processing conveyor systems or the like, as shown and described.
